UNITED STATES PATENT OFFICE.

ALFRED J. FLAUDER, OF BRIDGEPORT, CONNECTICUT, ASSIGNOR TO THE WEIDLICH BROTHERS MANUFACTURING CO., OF BRIDGEPORT, CONNECTICUT, A CORPORATION OF CONNECTICUT.

DESIGN FOR A JEWEL-CASE.

44,633.

Specification for Design.

Patented Sept. 9, 1913.

Application filed July 10, 1913. Serial No. 778,386. Term of patent 3½ years.

To all whom it may concern:

Be it known that I, ALFRED J. FLAUDER, a subject of the King of Austria, and resident of Bridgeport, in the county of Fairfield and State of Connecticut, have invented a new, original, and ornamental Design for a Jewel-Case, of which the following is a specification, reference being had to the accompanying drawings, forming part thereof.

In the drawings: Figure 1, shows a top plan view of my novel design of jewel case. Fig. 2, is a front elevation of the same. Fig.

3, shows an end view as seen from the right of Figs. 1 and 2. Fig. 4 is a rear elevation, and Fig. 5 shows a left end view.

I claim:

The ornamental design for a jewel case as shown.

Signed at Bridgeport in the county of Fairfield and State of Connecticut this 28th day of June, A. D. 1913.

ALFRED J. FLAUDER.
